UNITED STATES PATENT OFFICE.

LOUIS L. SMITH, OF EDGEWOOD, PENNSYLVANIA, ASSIGNOR, BY MESNE ASSIGNMENTS,
TO THE WESTINGHOUSE GEAR AND DYNAMOMETER COMPANY, OF PITTSBURGH,
PENNSYLVANIA, A CORPORATION OF PENNSYLVANIA.

REDUCTION-GEARING.

1,228,493.

Specification of Letters Patent.

Patented June 5, 1917.

Application filed April 12, 1913. Serial No. 760,762.

To all whom it may concern:

Be it known that I, Louis L. Smith, a citizen of the United States, and a resident of Edgewood, in the county of Allegheny and State of Pennsylvania, have made a new and useful Invention in Reduction-Gearing, of which the following is a specification.

This invention relates to reduction gearing and as an object has the production of gearing for transmitting power from high speed motors, such as turbines, to apparatus to be run at lower speeds, such, for instance, as the propeller shafts of ships, direct current generators, and centrifugal pumps.

15 A further object of this invention is the production of relatively cheap and simple means in reduction gearing for permitting automatic adjustment and distribution of the tooth pressures during the transmission of power.

20 A still further object is the production in reduction gearing of simple and relatively cheap means for taking care of slight misalignment between the shafts of the operating gearing members making up the reduction gearing.

25 These, as well as other objects which will readily appear to those skilled in this art, I attain by the device described in the specification and illustrated in the drawings accompanying the same and forming a part of this application, and throughout which like elements are denoted by like characters.

George W. Melville and John H. Macalpine jointly have invented several reduction gearing devices for obtaining automatic distribution and adjustment of tooth pressures in reduction gearing. George Westinghouse has made a number of inventions relating to 30 reduction gearing and he has in a number of cases with which I am familiar supported one of the gear members of reduction gearing upon fluid supported devices so as to obtain an automatic distribution and adjustment of the tooth pressures. Charles Algernon Parsons on January 23, 1894, obtained U. S. Patent No. 513367 for bearings for steam turbines and in said patent he describes a bearing made up of a number of 35 concentric bushes or nested tubes between which oil films are maintained for preventing or lessening the vibration caused by high speeds of rotation in the shafts of steam turbines.

For the purpose of attaining cheaply and easily the objects sought by said Melville and Macalpine and said Westinghouse, I utilize bearings similar to those disclosed by the said Parsons for one of the gears of a reduction gearing apparatus. My invention 40 broadly consists in journaling the pinion member of spur gearing in bearings employing in their make-up a number of oil films so maintained that the pinion member practically floats and is free to move within the 45 necessary limits and in the preferred form the movements of the pinion due to its floating are limited to movements in the plane perpendicular to the plane including the axes of the gear and pinion and which 50 includes the axis of the pinion, and the pinion is mounted so as to be capable of adjusted movement in the plane including the axes of the gear and pinion.

For the purpose of fully illustrating my 55 invention but with no idea of limiting the same to certain specific details, I have shown the invention as applied to spur gearing in which the gear and pinion members are provided with reversely arranged spiral 60 teeth, as in the ordinary form of herringbone gearing.

In the drawings:

Figure 1 is a plan view of a reduction gearing device embodying this invention 65 and the cellular bearings for supporting the pinion member are shown in longitudinal section;

Fig. 2 is a transverse sectional view of the device shown in Fig. 1, on the line 2-2 of 70 Fig. 1;

Fig. 3 is a detail longitudinal section of one of the cellular bearings shown in Fig. 1; and

Fig. 4 is a transverse sectional view of 75 said bearing;

Fig. 5 is a fragmentary view partially in plan and partially in section of a modified form of this invention;

Fig. 6 is a view partially in elevation and 80 partially in longitudinal section of a modified form of this invention and illustrates means for supplying the oil for the oil films;

Fig. 7 is a transverse sectional view of the 85 form of cellular bearing shown in Fig. 6; and

Fig. 8 is a view partially in elevation and 90 partially in section of a special form of re-

duction gearing to which this invention has been applied, the special form of gearing having been invented by Georg Duffling of Cologne, Germany.

5 In the device illustrated in Figs. 1 to 5 inclusive a gear member 10 consisting of two sets of gear teeth 11 and 12 is mounted on a shaft 13 adapted to be connected to the apparatus to be run at a reduced speed, such 10 as a propeller shaft, a direct current generator, or a centrifugal pump. The shaft 13 is journaled within suitable bearings 14 and 15 carried in a casing member 16.

A pinion member which consists of a 15 shaft 17 provided with two sets of oppositely arranged spiral teeth 18 and 19, meshes with the gear member. The shaft 17 is journaled within cellular bearings 20, 21, and 22. Each of these bearings is preferably made up of a central bearing member 23 in which the shaft 17 turns or runs. The central bearing member 23 is provided with a central flanged portion 24, and end collars 25 and 26 threaded onto the central member 23. Between the central flange 24 and each of the end rings 25 and 26 are a number (preferably three, 27, 28, and 29) of bushes or tubes one fitting over the other with slight freedom of fit and closely fitting between the central flange 24 and the end rings. These bushes or sleeves are provided with drilled oil ducts 30.

The cellular bearing fits within an outer bearing shell 31 with slight freedom of fit 35 and the outer surface of the shell 31 at its center is formed in the nature of a sphere at 32 and this portion rests within a cylindrical portion 33 of the bearing shell 34 which, in turn, is bolted as at 35 to a base 40 frame 16.

In order to independently adjust bearings 20, 21, and 22 so as to adjust shaft 17 with relation to shaft 13, adjusting struts 40, 41, and 42 are utilized and these pass through 45 openings formed for that purpose in the pinion frame and bear against central flange 24 of the bearing tubes 23 and are adjustable by means of bolts 43.

Besides serving as means for adjusting 50 shaft 17 with relation to shaft 13, these struts limit the movements of the pinion member allowed by the cellular bearings to movements in the plane perpendicular to the plane including the axes of the gear and 55 pinion (and which includes the axis of the pinion).

Oil under pressure derived from a suitable source must be pumped or forced into the bearings and for this purpose I provide 60 an inlet pipe 50. The oil entering through said pipe will be forced in between the nested bushings through the oil ducts in the bushings themselves and through the oil ducts 51 drilled in the outer shell 31. The 65 oil between the nested bushings offers great

resistance to movements of the tubes or bushings relatively to each other due to the hydraulic and capillary resistance of the oil between the bushings and while movement of the pinion member is permitted in 70 the plane perpendicular to the plane including the axes of the gear and pinion and which includes the axis of the pinion, still it is so resisted that a distribution and adjustment of the tooth pressures encountered 75 during the operation of the gearing will be automatically obtained. In Fig. 5 cellular bearings substantially the same as those shown by said Parsons in his said patent are shown and in these forms no means are 80 shown for limiting the movements of the pinion to movements in the plane perpendicular to the plane including the axes of the gear and pinion and which includes the axis of the pinion, but free movements between certain limits are allowed. In Figs. 85 6 and 7, however, the shaft 17^a is journaled within a split bearing made up of halves 18^a and 19^a. Above and below the bearing a number of leaves or plates 20^a of suitable 90 metal are located. A bearing box 30^a surrounds the bearing member and the leaves and is formed so that the bearing member snugly fits the sides thereof while freedom is allowed above and below the leaves or 95 films for slight relative movement therebetween. In the space for allowing such movement oil will be forced under pressure and the shaft will be floated but restrained in its movements by the sides of the bearing box 100 to the plane heretofore described.

In accordance with the provisions of the 105 patent statutes I have described the principle of operation of my invention together with the device which I now consider to represent the best embodiment thereof, but I desire to have it understood that the device shown is only illustrative and that the invention can be carried out in other ways.

What I claim is:

1. A reduction gearing comprising intermeshing gears, supporting means for one of said gears for allowing relative angular motion between the shafts of the gears and comprising bearings spaced along the shaft 115 of one of the gears, each bearing comprising a central bearing member surrounding the shaft of the gear, a bearing support, concentric cylindrical sleeves surrounding the said central member and located between it and said support, and means for delivering lubricant under pressure to each bearing, whereby a thin film of lubricant is maintained between adjacent sleeves.

2. A reduction gearing comprising inter- 125 meshing gears, in combination with supporting means for one of the gears, permitting relatively angular motion between the longitudinal axes of the gears, and comprising a stationary support for the angularly 130

movable gear, bearing sleeves in which the angularly movable gear is journaled, means for forming a plurality of liquid films between each bearing sleeve and the stationary supporting means, and means for delivering liquid to said films.

3. A reduction gearing comprising intermeshing gears, in combination with supporting means for one of the gears, permitting relative angular motion between the longitudinal axes of the gears, and comprising bearings for the shaft of the angularly movable gear, means forming a part of each bearing for segregating a plurality of relatively thin liquid films which yielding support the shaft, and means for delivering liquid under pressure to the said films.

4. A reduction gearing comprising intermeshing gears, supporting means for one of the gears constructed to allow relative angular motion between the axes of the shafts of the gears, and comprising cellular bearings spaced along the shaft of the angularly movable gear, means for delivering liquid under pressure to the bearings, and means for limiting the movement of the shaft to a plane substantially perpendicular to the plane defined by the normal positions of the axes of the gears.

5. A reduction gearing comprising intermeshing gears, supporting means for one of the gears constructed to permit relative angular motion between the axes of the gears and comprising cellular bearings for the shaft of the angularly movable gear, means for delivering fluid under pressure to the bearings, means for limiting the angular motion of the angularly movable gear to a plane substantially perpendicular to the

plane defined by the normal positions of the axes of the gears, and means for adjusting the angularly movable gear toward and away from the other gear.

6. A reduction gearing comprising intermeshing gears, supporting means for one of said gears, constructed to allow relative angular motion between the gears and comprising cellular bearings spaced along the shaft of the gear, and means for admitting liquid under pressure to said bearings.

7. A reduction gearing comprising intermeshing gears, bearings spaced along the shaft of one of said gears, each bearing comprising concentric sleeves surrounding the shaft of the gear and having ducts for liquid formed therein, and means for delivering liquid under pressure to the ducts of said sleeves.

8. A reduction gearing comprising intermeshing gears, in combination with supporting means for one of the gears, permitting relative angular motion between the gears, and comprising cellular bearings spaced along the shaft of the angularly movable gear, each bearing comprising concentric sleeves surrounding the gear shaft, a bearing shell surrounding the concentric sleeves and provided with a spheroidal outer face having its maximum diameter intermediate its ends, and a bearing housing enclosing said shell and engaging the outer spheroidal face thereof.

In testimony whereof, I have hereunto subscribed my name this 8th day of April, 1913.

LOUIS L. SMITH.
